UNITED STATES PATENT OFFICE.

SAMUEL S. SPEICHER, OF URBANA, INDIANA.

BROADCAST SEED-SOWER.

SPECIFICATION forming part of Letters Patent No. 349,820, dated September 29, 1886.

Application filed May 14, 1884. Serial No. 131,428. (No model.)

To all whom it may concern:

Be it known that I, SAMUEL S. SPEICHER, a citizen of the United States, residing at Urbana, in the county of Wabash and State of 5 Indiana, have invented certain new and useful Improvements in Broadcast Seed-Sowers, of which the following is a specification, to wit:

This invention relates to hand seed-planters; and it consists in certain peculiarities of 10 construction and arrangement of the same, whereby the machine is simplified and cheapened and disposed in better position for carrying, while preserving its perfect operation, substantially as will be hereinafter more fully set 15 forth and claimed.

In order to enable others skilled in the art to which my invention appertains to make and use the same, I will now proceed to describe its 20 construction and operation, referring to the accompanying drawings, in which—

Figure 1 is a plan view of the bottom of my device with the distributing-wheel and a portion of the operating-bow. Fig. 2 is a longitudinal vertical section of the same; Fig. 3, a 25 detail section of the bow-guide.

A represents the bottom of my seed-receptacle, formed with the seed-opening a , and provided with the usual bag, A', of canvas or other suitable flexible material, tacked to the bottom 30 in the usual way, for holding the seed.

I construct the bottom of my seed-receptacle of a single board or plate, A, placed on an incline and hollowed out at a' on one side, to fit the body, while in front of this hollow it is preferably broadened, as at a'' , in order to throw 35 more seed in front of the body and preserve a proper balance of the machine.

Beneath the bottom A is secured a longitudinal brace, B, in the forward or lower end 40 of which is stepped the distributing-wheel C, provided with radial arms C', in the usual or any desired form. Below the wheel C its journal is provided with a spool, e, and the brace B is formed with a transverse hole, b, through 45 which passes the operating-bow D, having a cord, D', wound around the spool in the usual way.

Beneath the seed-opening a in the bottom of the seed-receptacle is placed a slide or valve, 50 E, of the usual form, having a shank or stem, e,

connected to a lever, E', by which the valve is drawn back to expose more or less of the opening a . This valve is held in place when opened by means of a stop. (Not shown in this case, as it is described and claimed in another application which I now have pending.) The forward side of the valve is provided with a forked extension, e', which is engaged and vibrated by the cranked upper end of the spindle e' of the distributing-wheel C. The transverse hole or 55 bow-guide b, as represented in Figs. 2 and 3, is beveled off on both sides of the brace to allow the bow free play and let the hand of the operator assume a position nearer to or farther from the body, as may be more easy and natural, without reference to the position of the seed-receptacle.

I do not desire to be understood as confining myself to the exact form of construction of the guide as shown. It is evident that the same 70 may be changed without departing from the spirit of my invention.

The bag is hung from the shoulders, in the manner usually used in such devices, by straps properly disposed to support it in working 75 position. The hollowed portion of the bottom allows the bag to fit closely to the body, and disposes the bulk of the seed in the best position for carrying it. The bow is pushed back and forth to operate the wheel C and 80 scatter the seed that falls upon it, and in this motion the operator is free to keep his hand in the most comfortable position, the bow working freely through the beveled hole b, whether at right angles or not.

I am aware that heretofore the bottoms of broadcast-seeders have been hollowed out, and I do not claim the same, broadly; but

What I do claim, and desire to secure by Letters Patent, is—

1. In a broadcast-seeder, the bottom plate, A, hollowed out upon one side, as at a' , to fit the body, and made broader in front than in rear of this hollow to better dispose of the bulk and weight of the seed, substantially as shown and 95 described.

2. In a broadcast-seeder, the combination, with the main body of the device provided with a vibrating valve and a distributing-wheel, of an operating-bow and a guide, whereby the bow 100

may be operated at any convenient angle with the main frame, substantially as and for the purpose set forth.

3. In a broadcast-seeder, the combination, with the reciprocating operating-bow, of a bow-guide having a hole formed flaring at both ends, whereby the bow-hand may be thrown to or from the body in the position found most comfortable by the operator, substantially as shown and described.

4. In a broadcast-seeder, the bottom A, hollowed at a' and having a seed-opening, a , and

the brace B, having a double beveled hole, b , in combination with the distributing-wheel C, vibrating valve E, and the bow D, all constructed 15 and arranged to operate substantially as and for the purpose set forth.

In testimony whereof I affix my signature in presence of two witnesses.

SAMUEL S. SPEICHER.
